UNITED STATES PATENT OFFICE.

HARVEY J. LOISELLE, OF CHIPPEWA FALLS, WISCONSIN.

CHILD'S COASTER WAGON.

1,408,616.

Specification of Letters Patent. Patented Mar. 7, 1922.

Application filed January 21, 1921. Serial No. 438,988.

To all whom it may concern:

Be it known that I, HARVEY J. LOISELLE, a citizen of the United States, residing at Chippewa Falls, in the county of Chippewa 5 and State of Wisconsin, have invented certain new and useful Improvements in a Child's Coaster Wagon; and I do hereby declare the following to be a full, clear, and exact description of the invention, such as 10 will enable others skilled in the art to which it appertains to make and use the same.

The invention relates to vehicles and more particularly to toy wagons whereby children may coast and at all times have the device 15 under control so as to properly steer to avoid collision with objects and enable a deviated course to be followed.

The invention provides a child's wagon having an open bottom, preferably of slats, 20 front and rear axles firmly braced, and a handle having pivotal connection with the front axle and adapted to extend rearwardly over the bottom to provide convenient and positive steering means.

25 The invention furthermore provides a wheeled toy simple and light in structure and durable so as to withstand hard usage and enable the same to be effectively controlled by a child.

30 Other objects and advantages will be apparent and suggest themselves as the nature of the invention is understood.

While the drawings illustrate an embodiment of the invention, it is to be understood 35 that in adapting the same to meet different conditions and requirements, various changes in the form, proportion and minor details of construction may be resorted to without departing from the nature of the invention.

40 Referring to the drawings hereto attached and forming a part of the specification,

Figure 1 is a top plan view of a toy wagon embodying the invention,

Figure 2 is a side view of the wagon,

45 Figure 3 is a front view of the device,

Figure 4 is a rear view of the vehicle, and

Figure 5 is a detail view showing more clearly the parts associated with the front axle and steering wheel mounted thereon.

50 Corresponding and like parts are referred to in the following description and designated in the several views of the drawings by like reference characters.

The vehicle comprises a bottom or bed 1 which is preferably of open structure comprising a plurality of longitudinally disposed slats. Cross pieces 2 connect the slats and form reinforcing means therefor. Front bolsters 3 and rear bolsters 4 are provided for supporting the front and rear 60 axles, respectively, and are connected to the bed or bottom in any substantial and convenient way. A forwardly extending reach or brace 5 constitutes a stay for the rear bolster 4. Oppositely disposed braces 6 65 stiffen and stay the front bolster. The rear axle 7 supports the bolster 4 and is connected thereto in any manner. The rear axle 7 is fixed and is provided with supporting wheels in any suitable way. The 70 front axle 8 is pivoted and has a king bolt connection with the bolster 3 so as to turn for proper steering.

A handle 9 is connected at one end by means of curved strap irons 10 with the 75 forward ends of hounds 11 which are connected to the front axle 8. The hounds 11 consist of strap irons which are attached at their lower ends to the extremities of the axle 8 and incline upwardly and forwardly 80 and have the lower ends of the strap irons 10 pivotally connected thereto by means of the fastenings 12. The curved connections 10 admit of the handle 9 extending over the bed of the vehicle. This provides for positive and safe control of the wagon when 85 coasting. The handle also provides convenient means for drawing the wagon in a manner well understood.

A device constructed in accordance with 90 the present invention provides a wagon specially adapted for children since it is light, strong and durable and capable of being controlled at all times with safety to the child. The structure is such as to admit of the 95 vehicle being cheaply manufactured.

It is also noted that the wagon is light, strong, durable and compact, the handle falling back and lying close on the body so that the device may be conveniently handled 100 and carried upon a street car, automobile or other vehicle. The wagon is also quiet and smooth running.

What is claimed is:

A child's coaster wagon comprising a 105 slatted bottom, front and rear bolsters con-

necting the slats of the bottom, a forwardly extending brace for the rear bolster, oppositely disposed braces for the front bolster, a rear axle fixedly connected to the rear bolster, a front axle having pivotal connection with the front bolster, hounds inclining upwardly and forwardly from the ends of the front axle, a handle, and a curved con-

nexion between the handle and hounds and having pivotal connection with the latter.

10

In testimony whereof I affix my signature in presence of two witnesses.

HARVEY J. LOISELLE.
